UNITED STATES PATENT OFFICE.

HANS R. SETZ, OF ST. LOUIS, MISSOURI, ASSIGNOR TO FULTON IRON WORKS, OF ST. LOUIS COUNTY, MISSOURI, A CORPORATION OF MISSOURI.

PUMP-REGULATOR.

1,116,494.

Specification of Letters Patent. Patented Nov. 10, 1914.

Application filed July 11, 1914. Serial No. 850,465.

To all whom it may concern:
Be it known that I, HANS R. SETZ, a citizen of the United States of America, and a resident of the city of St. Louis, State of Missouri, have invented certain new and useful Improvements in Pump-Regulators, of which the following is a full, clear, and exact description, reference being had to the accompanying drawings, forming a part 10 of this specification.

My invention relates to a regulating device adapted to be associated with fuel pumps of internal combustion engines of the "Diesel" type, the present invention 15 being an improvement on the pump regulating device shown in U. S. Patent No. 1,076,915, issued to the Fulton Iron Works Oct. 28, 1913. The structure shown in this prior patent includes a diaphragm deflectible in response to pressure exerted by the 20 liquid in a pump chamber so as to vary the capacity of the pump chamber. The earlier structure also includes a non-yieldable stop member adjustably supported opposite the 25 central portion of the diaphragm, and serving to limit the movements of the diaphragm, the stop member being under the control of an engine governor. The yieldable diaphragm changes in shape when it is 30 deflected to engage the rigid stop member, and since this inflexible stop member cannot assume the different shapes of the diaphragm, it does not absolutely control the movement of said diaphragm.

35 The object of the present invention is to provide a flexible diaphragm stop adapted to be deflected to conform substantially to the shape of the diaphragm when the latter is deflected, thereby positively controlling 40 the movement of the diaphragm. While my new diaphragm stop is a flexible structure, it is preferably composed of a number of rigid sections which do not yield in response to the pressure exerted by the diaphragm.

45 Figure I is a longitudinal section, partly in elevation, illustrating a fuel pump provided with my regulating device. Fig. II is an enlarged vertical section showing the flexible diaphragm stop and the elements associated therewith. Fig. III is a fragmentary view showing a portion of the diaphragm, the flexible diaphragm stop, and the yieldable device located between the diaphragm and the diaphragm stop. Fig. IV is a de-

tail view of one of the segments which form 55 the flexible diaphragm stop.

1 designates a pump cylinder, and 2 a plunger operable in said cylinder. The plunger 2 is designed to be driven by a shaft 3 forming part of an internal combustion engine, said shaft 3 being provided with an eccentric 4 for driving a connecting rod 5, and the latter being pivoted to a cross head 6 fixed to the pump plunger 2. A pump chamber 7 adapted to receive the 65 plunger 2, is designed to receive a supply of liquid fuel, for instance oil, and the fuel received by the pump chamber is forced therefrom to the cylinder of an internal combustion engine. The fuel to be forced 70 to the engine passes from a supply pipe 8 to an inlet chamber 9 adjoining the pump chamber, and when the pump plunger moves on its suction stroke a suction valve 10 opens automatically to admit the fuel to the pump 75 chamber 7. During the power strokes of the plunger, the valve 10 is forced to its seat by a spring 11 as well as by the pressure of the fuel in the pump chamber, and the discharge valve 12 opens to permit the 80 flow of fluid to the engine cylinder. The plunger 2 partakes of a uniform movement, the length of each stroke of the plunger being determined by the movement of the eccentric 4. However, the volume of fuel 85 discharged from the pump chamber is regulated or controlled by a governing device as will be presently described.

Adjacent to the pump chamber 7 is a diaphragm chamber 13 communicating with 90 the pump chamber through a port 14 which permits the liquid fuel entering into the pump chamber to pass therefrom into said diaphragm chamber.

15 designates a yieldable diaphragm securely held at its margin by a chambered member 16 secured to the pump structure and serving as a guide for an adjusting rod 17. The diaphragm 15 is adapted to be deflected by the pressure of the fluid confined 100 between the valves 10 and 12 during the power strokes of the plunger 2, thereby enlarging the space for the fuel confined between said valves. When the diaphragm is deflected by the fluid pressure in the pump 105 chamber some of the fuel escapes into the diaphragm chamber instead of passing out through the discharge port 18, and the vol-

ume of fuel to be discharged is regulated by limiting the movements of the diaphragm 15, permitting a considerable deflection of the diaphragm when it is desired 5 to decrease the fuel supply, and preventing the diaphragm from deflecting when the maximum fuel supply is required.

The means for regulating the movement of the diaphragm to vary the fuel supply, 10 in accordance with the load on the engine, comprises a flexible stop device arranged behind the diaphragm and adapted to be deflected to provide an abutment conforming substantially to the shape of the diaphragm when the latter is deflected. The flexible stop device preferably comprises a series of segments 20 arranged in a circular chamber 21 at the inner end of the member 16, said segments being fitted together to 15 produce a substantially circular stop device. The outer ends of the segments 20 are fitted to walls of the chamber 21 and the inner ends of said segments are seated in an annular groove formed by collars 22 and 23 at 20 the inner end of the adjusting rod 17. When the adjusting rod and the segments 20 occupy the position shown in full lines Fig. I and Fig. II, the diaphragm 15 is prevented from deflecting into the chamber 21 25 and the liquid fuel displaced by the pump plunger 2 is then discharged through the discharge port 18. However when the adjusting rod 17 is moved to deflect the segments 20 to the position shown in dotted 30 lines Fig. II, a portion of the fuel displaced by the pump plunger is forced into the diaphragm chamber 13 so as to enlarge said chamber by deflecting the diaphragm to the 35 position seen in dotted lines, thereby permitting a portion of the displaced fuel to remain in the diaphragm chamber instead of passing out through the discharge port 18. The deflectible stop device consisting of the rigid segments 20 rockably mounted in 40 the chamber 21, is adapted to be deflected through the medium of a governor 30 co-operable with the shaft 3 by which the plunger 2 is driven, and said governor may be of any suitable construction. In the 45 construction herein illustrated, the governor includes a sleeve 31 slidably longitudinally of the shaft 3, and said sleeve has connected to it a lever 24 pivotally supported at 50 and connected to a slidable cam 26 by means of a link 27. The cam member 26 is provided with a cam groove 29 adapted to receive a cam block 28 secured to the outer end of the adjusting rod 17.

The series of segmental stop members 20 55 surrounding the inner end of the adjusting rod 17 may be deflected as previously pointed out to provide an abutment face corresponding substantially to the shape of the diaphragm when the latter is deflected, and 60 it is desirable to provide a substantially

smooth abutment face, devoid of shape or projecting corners which would wear away the adjacent face of the diaphragm. Therefore, if desired, a yieldable protector 31 may be interposed between the diaphragm and the segmental stop members 20. The protector I have shown is a circular member provided with a series of yieldable tongues which preferably overlie the corners of the segmental stop members 20.

I claim:—

1. The combination of a housing containing a pump chamber, means operable to force fluid from said chamber, a deflectible diaphragm exposed to said pump chamber, the diaphragm being changeable in shape in response to pressure exerted in said pump chamber, and a deflectible stop device adjustable with relation to said diaphragm and adapted to change in shape during adjustment to provide an adjustable diaphragm stop conforming substantially to the shape of said diaphragm.

2. The combination of a housing containing a pump chamber, means operable to force fluid from said chamber, a deflectible diaphragm exposed to said pump chamber, the diaphragm being changeable in shape in response to pressure exerted in said pump chamber, a deflectible stop device for limiting the movements of said deflectible diaphragm, said deflectible stop device being adapted to be deflected to provide an abutment conforming substantially to the shape of the diaphragm when the latter is deflected, and means for adjusting said deflectible stop device.

3. The combination of a housing containing a pump chamber, means operable to force fluid from said chamber, a deflectible diaphragm exposed to said pump chamber, the diaphragm being changeable in shape in response to pressure exerted in said pump chamber, a deflectible stop device for limiting the movements of said deflectible diaphragm, said deflectible stop device comprising a series of movable sections adapted to be adjusted to provide an abutment conforming substantially to the shape of said diaphragm when the latter is deflected, and means for adjusting said sections.

4. The combination of a housing containing a pump chamber, means operable to force fluid from said chamber, a deflectible diaphragm exposed to said pump chamber, the diaphragm being changeable in shape in response to pressure exerted in said pump chamber, a deflectible stop device for limiting the movements of said deflectible diaphragm, said deflectible stop device comprising a series of movable sections adapted to be adjusted to provide an abutment conforming substantially to the shape of said diaphragm when the latter is deflected, and means for adjusting said sections, said

means including an adjusting member fitted to said sections.

5. The combination of a housing containing a pump chamber, means operable to force fluid from said chamber, a deflectible diaphragm exposed to said pump chamber, the diaphragm being changeable in shape in response to pressure exerted in said pump chamber, a deflectible stop device for limiting the movements of said deflectible diaphragm, said deflectible stop device comprising a series of movable sections adapted to be adjusted to provide an abutment conforming substantially to the shape of said diaphragm when the latter is deflected, and means for adjusting said sections, said means including an adjusting rod surrounded by and fitted to said sections.

6. A governing device comprising a housing provided with a pump chamber, means for forcing fluid from said chamber, a deflectible diaphragm exposed to said pump chamber, the said diaphragm being changeable in shape in response to pressure exerted against fluid forced from the pump chamber, a deflectible stop device for limiting the movements of said deflectible diaphragm, an engine governor, and means, operable by said engine governor, for adjusting said deflectible stop device.

7. A governing device comprising a housing provided with a pump chamber, means for forcing fluid from said chamber, a deflectible diaphragm exposed to said pump chamber the said diaphragm being changeable in shape in response to pressure exerted against fluid forced from the pump chamber, a deflectible stop device for limiting the movements of said deflectible diaphragm, said deflectible stop device being adapted to be deflected to provide an abutment conforming substantially to the shape of said diaphragm when the latter is deflected, a governor, and means, operable by said governor for adjusting said deflectible stop device.

8. A governing device comprising a housing provided with a pump chamber, means for forcing fluid from said chamber, a deflectible diaphragm exposed to said pump chamber, the said diaphragm being changeable in shape in response to pressure exerted against fluid to be forced from the pump chamber, a deflectible stop device, adjustable with relation to said diaphragm and adapted to change in shape during such adjustment to provide an adjustable diaphragm stop conforming substantially to the shape of the diaphragm, an engine governor, and means, operable by said engine governor, for adjusting said deflectible stop device.

9. A governing device comprising a housing provided with a pump chamber, means for forcing fluid from said chamber, a

deflectible diaphragm exposed to said pump chamber, the said diaphragm being changeable in shape in response to pressure exerted against fluid forced from the pump chamber, a deflectible stop device comprising inflexible rocker members; an engine governor, and means, operable by said engine governor, for adjusting said rocker members to limit the movements of said diaphragm.

10. A governing device comprising a housing provided with a pump chamber, means for forcing fluid from said chamber, a deflectible diaphragm exposed to said pump chamber, the said diaphragm being changeable in shape in response to pressure exerted against fluid forced from the pump chamber, a substantially circular stop device comprising a series of segmental stop members adapted to be deflected to provide an abutment conforming substantially to the shape of, and serving as a stop for, said diaphragm when the latter is deflected, a governor, and means operable by said governor for adjusting said stop device.

11. A governing device comprising a housing provided with a pump chamber, means for forcing fluid from said chamber, a deflectible diaphragm exposed to said pump chamber, the said diaphragm being changeable in shape in response to pressure exerted against fluid forced from the pump chamber, a deflectible stop device for limiting the movements of said diaphragm, said deflectible stop device comprising a series of segmental members arranged together to produce a substantially circular structure; an adjusting rod provided with an annular groove in which the inner ends of said segmental members are seated, and an engine governor associated with said adjusting rod to move the latter longitudinally, thereby deflecting said stop device.

12. A governing device comprising a housing provided with a pump chamber, means for forcing fluid from said chamber, a deflectible diaphragm exposed to said pump chamber, the said diaphragm being changeable in shape in response to pressure exerted against fluid forced from the pump chamber, a deflectible stop device for limiting the movements of said diaphragm, said deflectible stop device comprising a series of segmental members arranged to produce a substantially circular structure; an adjusting rod provided with an annular seat to which the inner ends of said segmental members are fitted, and an engine governor associated with said adjusting rod to move the latter longitudinally, thereby deflecting said stop device.

13. The combination of a housing containing a pump chamber, means for forcing fluid from said chamber, a deflectible diaphragm exposed to said pump chamber, the diaphragm being changeable in shape in response to pressure exerted in said pump

chamber, a deflectible stop device, adjustable with relation to said diaphragm and adapted to change in shape during adjustment to provide an adjustable diaphragm stop 5 forming substantially to the shape of said diaphragm, and a yieldable protector interposed between said diaphragm and stop device.

14. The combination of a housing containing 10 a pump chamber, means for forcing fluid from said chamber, a deflectible diaphragm exposed to said pump chamber, the diaphragm being changeable in shape in response to pressure exerted in said pump

chamber, a deflectible stop device for limiting the movements of said deflectible diaphragm, said deflectible stop device comprising a series of sections adjustable to provide an abutment conforming substantially to the shape of the diaphragm when 15 the latter is deflected; and a yieldable protector interposed between said deflectible diaphragm and said stop device. 20
